UNITED STATES PATENT OFFICE.

JOHN F. WILMOT, OF JAMESTOWN, NEW YORK.

FOLDING CHAIR.

1,242,406.

Specification of Letters Patent.

Patented Oct. 9, 1917.

Application filed February 26, 1916. Serial No. 80,728.

To all whom it may concern:

Be it known that I, JOHN F. WILMOT, a citizen of the United States, residing at the city of Jamestown, in the county of Chautauqua and State of New York, have invented certain new and useful Improvements in Folding Chairs, of which the following, taken in connection with the accompanying drawings, is a specification.

10 The invention relates to folding or disappearing chairs and particularly for use in automobiles; and the object of the improvement is to provide a chair construction which can be folded into the floor of the car when not in use and which may be easily raised into the set up position and when so set up the parts are interlocking upon one another so that the chair cannot be pushed into the folded position without raising the 15 seat portion, the back and seat portions also having connective mechanism whereby they are balanced in relation to one another by the weight of the occupant, to provide an automatic reclining back; and the invention 20 consists in the novel features and combinations hereinafter set forth and claimed.

In the drawings, Figure 1 is a perspective sectional view of the chair in the folded position in a box in the floor of the car and 25 forming a portion of said floor. Fig. 2 is a perspective view of the set up chair showing the balancing mechanism for the reclining seat and back. Fig. 3 is a crosswise sectional view of the seat portion in the 30 set up position showing the lower portion of the back, the upper portion being broken away. Fig. 4 is a perspective view of the joint between the back and the extension of the lower corner of said back at each side 35 whereby said back connects with the seat at each side with toggle joints; and Fig. 5 is a side elevation of said joint showing the stop or limit for the reclining movement of the back. Fig. 6 is a detail elevation of one 40 of the top links connecting the seat portion to the supporting frame or pan. Fig. 7 is a perspective view of the chair partially 45 opened or set up, the different steps to the set up position being shown in dotted line 50 illustrating how the seat portion of the chair must be raised in order to set up the same and showing the construction and arrangement of the different parts. Fig. 8 is a 55 sectional view of the floor box or pan for the folding chair and a front elevation of

said chair in the set up position. Fig. 9 is a sectional view at line 9—9 in Fig. 8 showing the locking relation of the links and the seat portion to the upright supporting pan or frame. Fig. 10 is a sectional view of the floor frame showing the 60 spring catch for holding the chair in the set up position.

Like numerals of reference refer to corresponding parts in the several views. 65

The numeral 10 designates the box or pit in the floor of the car body into which the chair folds.

The folding chair consists of a supporting portion 11, a seat portion 12 and a back portion 19 which portions are hingingly connected to one another and are constructed in the following manner: The supporting portion consists of a pan or frame 11 of the desired height which fits and is pivotally 70 attached within the box or pit 10. The bottom of the pan 11 forms the closure of said pit or box 10 when in the folded position having a carpet or covering thereon corresponding to the carpet or covering of the remainder of the floor of the car so that when folded it forms a continuation of said covering only showing the outline of the shape of the pan 11 and pit 10. 75

The seat portion 12 consists of two seat 80 supporting bars 26, one at each side, which are sufficiently strong to uphold the weight of the occupant of the chair as said supporting bars 26 draw across the top of the supporting frame or pan 11. A seat pan 12' is 85 provided which has angular sides 32 which normally rest upon the support bars 26.

The seat pan 12' is preferably made with the angular flanged sides 32 which have the wooden angle strips 33 fitting over the same 90 for the attachment of the upholstering materials for the seat. The front end of the pan 12' is closed by a wooden cross bar 34 which has a lengthwise groove 35 therein within which a cross rod 36 is placed which 95 extends across the front of the seat pan 12' and through the sides thereof for the pivotal attachment of the front end of the seat pan 12' so that it may be raised and lowered 100 at its rear end, hinging from the front end of said seat. The rear end of the pan 12 is preferably closed by means of the wooden cross bar 37 to which the upholstering materials can be attached, which cross bar 37 105 is securely attached to the metal pan 12'. 110

The back portion 19 preferably consists of a sheet metal plate curved to conform to the shape of the top of said seat and to make a comfortable back support for the occupant, of size and shape to fold entirely out of the way upon said seat portion within the box 10.

The seat portion 12 is attached to the supporting pan or frame 11 by means of two pairs of links 13 and 14, the pair of links 13 being attached about midway of the length of the pan at 13' on each side so as to fold within said pan. Said links 13 are pivotally attached to the ends of the seat support bars 26 which ends are the front ends of said support bars 26 when in the set up position, so that said links 13 stand vertically when in said set up position, being shaped to gradually widen from their lower ends toward their upper ends so that they brace against the bottom of the pan 11 and hold the front ends of the seat support bars 26 firmly in position as said bars rest across the upper end of the pan 11 in said set up position.

The pair of links 14 one at each side are L-shaped each having the angular projection 15 at one end which is pivotally attached to projecting lugs 16 on the upper end of the pan 11 so that when said links 14 are turned over into the set up position and rest upon the upper flanged end of the pan 11, the projections 15 extend downward to the point 17 of pivotal attachment for each link 14 to each lug 16 and draws firmly across the upper end of the pan 11. The opposite ends of the links 14 are attached at 18 about midway of the length of the support bars 26, that is, the point 18 is the point to which the links 14 would normally extend along the bars 26 when pivotally attached to the lug 16 on the pan 11.

With the chair in the set up position the front ends of the seat support bars 26 are pivotally attached on the ends of the cross rod 36 as said ends extend through the sides of the seat pan 12', and the upper ends of the links 13 are also pivotally attached on said ends of said rod 36, thereby hinging said seat pan 12' at its front end to the seat support bars 26 and also to the links 13.

It is now apparent that with the double link connection 13 between the sides of the pan 11 and each side of the front end of the seat pan 12'; also with the double link connection 14 between the lugs 16 at each side of the top of the pan 11 and the middle points 18 of the seat supporting bars 26; the seat portion 12, consisting of the seat 12' and supporting side bars 26, may be swung outwardly from within the pan 11, as shown in Fig. 7, and then raised over the upper end of the pan 11, the double links 13 and 14 guiding said seat portion 12 in its turning movement until it rests upon the top

flange of the pan 11 and is firmly locked in position thereon by the two pairs of links 13 and 14, the links 13 assuming the vertical position when set up and bracing against the bottom of the pan 11, as shown in Fig. 9, and the links 14 binding over the angular flanged edge of the pan 11 with the leverage attained by the weight of the occupant of the chair upon the two seat supporting bars 26.

The back 19 is hinged between the two upwardly projecting rear ends 20 of the seat support bars 26 so as to fold over the seat pan 12' when in the folded position. It is obvious that the seat support bars 26 may be permanently attached to the angular flanged sides 32 of the seat pan and form a good folding chair. It is preferred, however, to hinge the back 19 to the seat portion 12 by means of double toggle links so that the rear portion of the seat pan 12' may be raised and lowered as desired by the occupant of the seat thereby giving the chair a reclining back when desired.

In the reclining back construction, a balancing adjustment of the seat pan 12' and the back 19 in relation to one another is attained by means of the angular back extensions 21 which are a part of the back portion 19 and secured thereto by means of the pair of double downward projecting lugs 22 one to each side which are attached to the upwardly projecting ends of the back extensions 21 by means of suitable pins, thereby forming a hinged joint between each back extension 21 and the back 19 permitting said back to fold over at said hinged joint but having a shoulder 23 on the back 19 which engages a similar shoulder 24 on the rear side of the back extension 21 so that a limited hinging movement is provided between the back 19 and the back extensions 21 at each side when it is desired to move said back 19 into the reclining position. Each of the seat supporting bars 26 has a lug 27 thereon which extends out over the downwardly and forwardly projecting extension 21 of the back 19, which lug 27 limits the upward movement of the rear portion of the seat 12 and the rearward movement of the back. A short link 25 is pivotally attached to each of the front ends of the two back extensions at one end and the other ends of said links 25 are pivotally attached to the sides of the seat pan 12'.

It is now apparent that with the pivotal attachment of the seat pan 12' on the rod 36 between the front ends of the seat support bars 26 on the links 13 and also the pivotal attachment of the seat pan 12' to the double links 25 a spaced distance from the rear end of the seat pan 12' and to the back extensions 21 at each side, a balancing adjustment of the seat and back in relation to one another is attained so that the occupant of the

seat may have any angle of inclination for the reclining back 19 which is desired up to the limitation of movement of said back by the shoulders 23 and 24 and the lug or 5 stop 27.

The lower end of the pan 11 is pivotally attached to the pan or frame 10 in the car floor by means of metal plates 28 attached to each side and extending within the frame 10. Said metal plates 28 have stops 29 attached thereto at each side at the position which holds the pan 11 vertically, the stop 29 at each side holding firmly against the pan 11 below the pivotal point 31 so that the 15 weight of the occupant of the seat being on the opposite side firmly supports the chair in the set up position. On this account it has not been usually found necessary to provide any means for locking the chair against 20 being pushed forward, though a spring catch 30 might be inserted in the rear of the lower end of the pan 11 at each side, which spring catches may be manually withdrawn when it is desired to fold the chair into the 25 frame 10.

The operation of the chair is exceedingly simple. A loop 38 is preferably attached to the rear edge of the center of the seat 12' for raising or setting up the chair by means 30 of which loop 38 the folded chair is first raised to the vertical position for the pan 11. The seat pan 12 and back 19 are then swung outwardly as shown in Fig. 7 from the pan 11, one hand being placed on the pan 11 to 35 steady the same; the pan 12 with the back 19 is then swung out and over the upper end of the pan 11, being guided by the links 13 and 14 in the movement of said pan 12 over the upper end of the pan 11 until said pan 12 40 rests upon said upper end of the pan 11 as hereinbefore described and shown in the drawings. The back 19 is then raised and the seat is ready for occupancy. If spring catches 30 are used they are preferably automatic in their action in setting up the chair 45 and only need to be manually withdrawn in order to fold the same.

It is apparent that the two seat supporting bars 26 which are pivotally attached to 50 the cross rod 36 on each side of the seat pan 12' at one end and to each side of the lower end of the back 19 at the other forms a chair frame of great strength which gives added rigidity to the entire structure. Changes 55 might be made in the construction and arrangement of the parts of the chair without departing from the spirit of the invention. For example, as hereinbefore stated, the seat pan 12' might be permanently attached to 60 the supporting bars or frame 26 and the extensions 21 on the lower end of the back with the links 25 might be omitted, or said back extensions and toggle link connection might be used with other forms of seat support- 65 ing frame. I accordingly do not limit my-

self to the particular form or arrangement shown.

I claim as new:—

1. A folding chair comprising two pans, links pivotally connecting said pans to one another to fold one within the other in the folded position and lock one across the upper end of the other in the set up position to thereby form a seat, means for supporting the upright pan in the set up position, 75 and a back hinged to said seat pan.

2. A folding chair comprising a seat portion, a support portion for said seat, a pair of links pivotally attached at one end to an end of said seat and at the other end intermediate of the ends of said supports, and a second pair of links pivotally attached at one end to an end of said support and at the other end intermediate of the ends of said seat portion to foldably attach said seat portion to said support portion. 85

3. A folding chair comprising a seat portion, a support portion for said seat having pivotal attachment to a support at one end and sidewise extending lugs on the opposite 90 end, a pair of links pivotally attached at one end about midway of the length of the sides of said support portion and to an end of said seat at the other, and a second pair of links with L-shaped ends pivotally attached to said lugs on said support portion and the other end pivotally attached about midway of the length of said seat portion to lockingly draw over the upper end of said support portion in the set up position. 95

4. A folding chair comprising a supporting member, a seat member pivotally connected to said supporting member by two pairs of links, one of said pairs of links lockingly drawing across the upper end of 100 said supporting member when in the set up position, a support for the lower end of said supporting member, and a folding back for said seat member.

5. In a folding chair, the combination of 110 a support, a seat member, and a forwardly swinging guide member connecting the forward end of the seat member with the support, said seat member being arranged to fold over the upper end of the support into 115 operative position.

6. A folding chair comprising a seat pan, supporting side bars for said seat pan, a support pan for said supporting side bars and seat pan, a pair of links pivotally attached about midway of the sides of said support pan at one end and to the front end of 120 said seat pan and side bars at the other end, lugs on the upper end of said support pan one to each side, a second pair of links having angular ends pivotally attached to said lugs one to each lug and the other ends pivotally attached about midway of the length of said seat support bars to cause said links and seat pan to lockingly bind across the 125 130

upper end of said support pan in the set up position, and a back hinged to said seat support bars and seat.

7. A folding chair comprising a supporting member, a seat member, and members arranged in pairs pivotally connecting said supporting and seat members to guide said seat member in its movement to and from a position at one side of said supporting member to and from a position upon the upper end thereof.

8. A folding chair comprising a supporting member, a seat member, links pivotally connecting said members and adapted to guide said seat member into operative position upon the upper end of said supporting member from a folded position within said supporting member.

9. A folding chair comprising a supporting member, a seat member, and links pivotally connecting said members and adapted to guide said seat member into operative position at right angles to said supporting member upon the upper end thereof from a position parallel therewith and at one side thereof.

10. In a folding chair, the combination of a supporting member, a seat member, and parallel swinging members pivotally connecting the supporting and seat members and adapted to interlock over the upper end of the supporting member when the seat member is in operative position.

11. In a folding chair, the combination of a supporting member, a seat member, and a pair of swinging members pivotally connecting said supporting and seat members and adapted to swing over and rest upon the upper end of the supporting member when the seat member is moved to operative position.

12. In a folding chair, the combination of a supporting member, a seat member, and a pair of members pivotally connected to said supporting member intermediate its ends at one end and the said seat member adjacent the forward end thereof at their opposite ends, said pair of members being adapted to swing against said supporting member when the seat member is moved to operative position.

13. In a folding chair, the combination of a support, a seat member, and a swinging guide member pivotally attached at one end to the seat member adjacent the forward edge thereof, said seat member being arranged to fold over the upper end of the support when in operative position with said guide member lying adjacent the forward side of said support.

14. In a folding chair, the combination of a support, a seat member, and a pair of guide members pivotally attached at one end to said support and at their opposite ends to said seat member intermediate the ends thereof, and a pivoted guide member pivotally attached to said seat member adjacent the forward edge thereof.

15. In a folding chair, the combination of a pivoted support adapted to be swung to an upright position, a seat member, and parallel guide members pivotally attached at one end to the forward side of said support and at their opposite ends to said seat member, said seat member and certain of said guide members being arranged to swing over and engage the upper end of said support when the seat member is moved to operative position and the other of said guide members being arranged to lie adjacent the forward side of said support when said seat member is in operative position.

16. In a folding chair, the combination of a support, a seat member, and a pair of swinging guide members pivotally attached at one end to the seat member adjacent the forward edge thereof, and at the other end to the support member intermediate its ends, said seat member being arranged to fold over the upper end of the support when in operative position with said guide member lying adjacent the forward side of said support, and means connecting the upper end of the support and the seat member to guide said seat member to and from its operative position.

In testimony whereof I have affixed my signature in the presence of two witnesses.

JOHN F. WILMOT.
